UNITED STATES PATENT OFFICE.

WILLIAM ESTY, OF LACONIA, NEW HAMPSHIRE; CHARLES W. TYLER, EXECUTOR OF
SAID WILLIAM ESTY, DECEASED, ASSIGNOR TO ESTY SPRINKLER COMPANY, OF
LACONIA, NEW HAMPSHIRE, A CORPORATION OF NEW HAMPSHIRE.

SPRINKLER FOR AUTOMATIC FIRE-EXTINGUISHING SYSTEMS.

1,230,469.

Specification of Letters Patent. Patented June 19, 1917.

Application filed August 12, 1916, Serial No. 114,582. Renewed May 7, 1917. Serial No. 167,065.

To all whom it may concern:

Be it known that I, WILLIAM ESTY, of Laconia, in the county of Belknap and State of New Hampshire, have invented a new 5 Sprinkler for Automatic Fire-Extinguishing Systems, of which the following is a specification.

Where automatic fire extinguishing systems equipped with sprinkler heads having 10 fusible valve retainers have been used in buildings in which destructive gases abound in quantities, in the course of a few years the sprinkler heads become so loaded with foreign matter that they fail to function 15 properly in the event of a fire. It has heretofore been proposed to protect the sprinkler heads from the action of gases by means of a cover of glass. The present invention consists in improvements upon covered sprinkler heads. The object of the improvement 20 is to insure the complete protection of the valve, valve seat, and fusible element of the sprinkler; and to insure the prompt release and removal of the cover in the event 25 of a fire so that the escape of water will not be substantially delayed.

The improvements are illustrated in the accompanying drawings wherein Figure 1, is a side elevation of the improved covered 30 sprinkler head, parts being broken away to facilitate the illustration. Fig. 2, is a central longitudinal section. Figs. 3 and 10, inclusive, are detailed views.

The sprinkler head itself is similar in 35 most respects to that illustrated in Letters Patent of the United States, granted January 9, 1917, No. 1,211,834.

The sprinkler head has a fitting A, adapted to be screwed in place on the pipe 40 system. This fitting has an annular outwardly projecting shoulder B, above which is an externally screw threaded section C, immediately below the valve seat. D, is the valve which is normally held in place by 45 a fusible strut E, which is interposed between the valve and an abutment F, carried by a frame G. This frame has a screw threaded collar H, which screws on to the section C, of the fitting. The side arms I, of 50 the frame G, which connect the collar H, and the abutment F, are rendered resilient, each having a plurality of reentrant bends J. By means of these bends the desired uniform re-

silence is readily secured. The frame also carries a distributor K.

The strut consists of a multiplying lever L, a valve lever M, and a frame lever N, united together by fusible solder.

The sprinkler head, as thus far described, is similar to that set forth in the above mentioned patent, excepting that in the present instance, the resilience of the frame is secured by the plurality of reentrant bends of each of the side arms.

The cover O, surrounds and covers the 65 entire resilient frame, the valve, the valve seat, and the fusible strut. It is desirably made of glass to resist the action of injurious gases. It is supported by two non-corrodible German silver disks P, and Q.

The outer disk P, has a circular opening R (Fig. 5), at its middle which fits over the section C, of the fitting, so that the disk rests upon the shoulder B. The inner disk Q, likewise has a central circular opening S (Fig. 70 4), which fits over the section C, so that the inner disk Q, rests upon the outer disk P.

Both disks having been put in place, the valve, strut and resilient frame are assembled, and the resilient frame is screwed down 80 on the section C, and tightly against the inner disk Q. In this way, the outer disk P, is seated firmly and with an air tight fit upon the shoulder B, and the two disks are firmly clamped together. At the same 85 time, the requisite and predetermined tension is put upon the strut through the resilient frame in the manner explained in the aforesaid prior patent.

The outer disk P, has an upturned annular peripheral flange T. The inner disk Q, has a similar flange U. The two flanges are concentric. The disk P, is of greater diameter than the disk Q, so that an annular groove exists between the two flanges 95 T, and U. The lower open end of the glass cover fits into this groove. The width of the groove is greater than the thickness of the glass, thus providing space for the insertion of a fusible cement such as paraffin wax, which is indicated at V. This fusible cement makes a gas tight joint between the glass cover and the supporting disks. At the same time the glass cover is firmly held in place without danger of moving laterally 100 as the result of jarring.

In this manner the valve, valve seat, and fusible strut are inclosed in a gas tight chamber.

In case of a fire the fusible cement V, 5 readily melts, the heat is radiated through the glass and the fusible strut is released, thus permitting the valve to open. When the valve is open the out-rushing water (or air if a dry system is employed) blows off 10 the glass cover which is readily displaced because of the melting of the cement V.

I claim:

1. A sprinkler for automatic fire extinguishing systems having, in combination, a fitting with a valve seat at its end and an outwardly projecting annular shoulder, and a screw threaded section between said shoulder and the valve seat; a non-corrodible disk with a peripheral flange resting upon the 15 said shoulder; a second non-corrodible disk with a peripheral flange resting upon the first named disk, the outer disk being of greater diameter than the inner disk so that an annular space or groove is constituted between the two flanges; a valve on the valve seat of the fitting; a frame fastened to the fitting and seating against the inner disk, thereby making an air tight joint 20 between the disks and the shoulder of the fitting; a separable fusible strut between the valve and the resilient frame; a glass cover fitting over the resilient frame, the valve seat, and the strut, the open edge of 25 said cover fitting into the groove between the flanges of the two disks; and a fusible cement in said groove forming an air tight joint between the glass cover and the disks.

2. A sprinkler for automatic fire extinguishing systems having a resilient frame with two side arms, each side arm having a plurality of reentrant bends.

3. A sprinkler for automatic fire extinguishing systems having, in combination, a fitting with a valve seat at its end and an outwardly projecting annular shoulder, and a screw threaded section between said shoulder and the valve seat; a disk with a peripheral flange resting upon the said shoulder; a second disk with a peripheral flange resting upon the first named disk, the outer disk being of greater diameter than the inner disk so that an annular space or groove is constituted between the two flanges; a valve on the valve seat of the fitting; a frame connected with the fitting; a separable fusible strut between the valve and the frame; a cover fitting over the frame, the valve seat, and the strut, the open edge of said cover fitting into the groove between the flanges of the two disks; and a fusible cement in said groove forming an air tight joint between the glass cover and the disks.

air tight joint between the disks and the shoulder of the fitting; a separable fusible 60 strut between the valve and the resilient frame; a cover fitting over the frame, the valve seat, and the strut, the open edge of said cover fitting into the groove between the flanges of the two disks; and a fusible cement in said groove forming an air tight joint between the glass cover and the disks. 65

4. A sprinkler for automatic fire extinguishing systems having, in combination, a fitting with a valve seat and an outwardly 70 projecting annular shoulder; a disk with a peripheral flange resting upon the said shoulder; a second disk with a peripheral flange resting upon the first named disk, the outer disk being of greater diameter than 75 the inner disk so that an annular space or groove is constituted between the two flanges; a valve on the valve seat of the fitting; a frame fastened to the fitting and seating against the inner disk, thereby making an air tight joint between the disks and the shoulder of the fitting; a separable fusible strut between the valve and the frame; a cover fitting over the frame, the valve seat, and the strut, the open edge of said cover 80 fitting into the groove between the flanges of the two disks; and a fusible cement in said groove forming an air tight joint between the glass cover and the disks.

5. A sprinkler for automatic fire extinguishing systems having, in combination, a fitting with an outwardly projecting shoulder and a valve seat; a disk with a peripheral flange resting upon the said shoulder; a second disk with a peripheral flange resting upon the first named disk, the outer disk being of greater diameter than the inner disk so that an annular space or groove is constituted between the two flanges; a valve on the valve seat of the fitting; a frame connected with the fitting; a separable fusible strut between the valve and the frame; a cover fitting over the frame, the valve seat, and the strut, the open edge of said cover fitting into the groove between the flanges of 100 the two disks; and a fusible cement in said groove forming an air tight joint between the glass cover and the disks. 95

In witness whereof, I have hereunto signed my name in the presence of two subscribing witnesses.

WILLIAM ESTY.
